SPRAYING DEVICE

Filed Dec. 14, 1928

UNITED STATES PATENT OFFICE

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS

SPRAYING DEVICE

Application filed December 14, 1928. Serial No. 326,135.

This invention relates particularly to spraying devices adapted for spraying liquids, for example, varnishes, etc.

The primary object of the invention is to provide an improved nozzle-container structure.

The invention is illustrated in the accompanying drawings, in which—

Fig. 1 shows brokenly and partly in section 10 a spraying outfit embodying the invention; Fig. 2 is a sectional view illustrating the use of a smaller container than that shown in Fig. 1; and Fig. 3 is a section taken as indicated at line 3 of Fig. 1.

In the construction illustrated, A designates an electric motor which surmounts a handle A' and is equipped with a rotary compressor A², the rotor of which is actuated by the armature-shaft of the motor; B designates a sectionally constructed spraying nozzle which in the illustration given is carried by the compressor; C designates a container-cap equipped with a ring C' which is connected with the nozzle; and C² and C³ designate containers of different sizes adapted to be interchangeably used in connection with the cap C.

The compressor is shown provided with a forwardly projecting hollow boss 1 which is internally threaded and which communicates with the outlet passage 1^a of the compressor. The details of the compressor need not be explained in the present application, but it may be stated that the compressor is provided with an air-inlet port 2. The air enters through the port 2, is compressed in the rotary compressor, and is expelled through the passage 1^a.

The nozzle B is shown as comprising three main sections 3, 4 and 5.

The section 3 is provided with a central air-passage 3^a; the section 4 is provided with a central air-passage 4^a with an inclined or oblique passage 4^b leading from the passage 4^a; with an annular passage 4^c in communication with the passage 4^b; and with forwardly converging passages 4^d leading from the annular passage 4^c; and the member 5 is provided with a central liquid-passage 5^a and with converging air-passages 5^b which com-

municate at their rear ends with the air-passages 4^d.

The member 3 is provided at its rear end with a threaded shank 3^b which is connected with the nipple 1. The member 4 is provided at its rear end with a threaded shank 4^e which has threaded connection with a bore 3^c with which the member 3 is provided at its front end.

The member 4 is provided with an annular surface, or seat, 4^f for the ring C', and with a shoulder 4^g against which the front edge of the ring abuts. The ring forms the outer wall of the annular passage 4^c; and the member 3 has its front end provided with a shoulder 3^d which abuts against the rear edge of the ring.

The front end of the member 4 and the rear end of the member 5 are provided with complementary annular recesses which provide an annular passage 6 at the meeting ends of the members.

The member 5 is provided at its rear end with a reduced threaded extension 5^e which screws into a central liquid passage 4^h with which the member 4 is provided. A vertical passage 4ⁱ in the member 4 communicates with the central passage 4^h. The lower end of the passage 4ⁱ is tapped and has screw connection with a liquid-tube 7 which depends into the container.

The nozzle-section 5 is equipped with a tip which comprises an inner tip-member 8 and an outer tip-member 9. The inner member is secured to the member 5 by means of an annular nut 10. This member has an inturned flange 10^a which engages an external flange at the base of the member 8, and it has an out-turned flange 10^b which is engaged by an annular nut 11 having screw connection with a flange 9^a of the cap-like tip-member 9. The member 8 has a central liquid-passage 8^a which registers with the passage 5^a, and has converging air-passages 8^b which communicate with the passages 5^b. At the meeting ends of these members 5 and 8 are complementary annular recesses forming an annular channel 12.

The outer tip-member 9 is provided with an outlet 9^b for the liquid and air. This pas-

sage 9^b may terminate in an orifice 9^c, which may be either a slot, or a circular orifice.

The container-cap C and the ring C' are preferably formed integrally with each other and connected by a stem, or neck, 13. The device may be formed of cast aluminum, for example. At its inner side, the cap is provided with a threaded socket 14 of suitable size to receive the threaded upper end of the small container C³, and is provided with a larger threaded socket 15 adapted to receive the threaded upper end of the large container C². These sockets are equipped with gaskets 14^a and 15^a, respectively.

15 Through the stem 13 connecting the ring C' with the cap C extends a passage 16 which connects the annular passage 4^c with the interior of the container C². The liquid-tube 7 is of smaller diameter than the passage 16.

20 The tube may be inserted through said passage and screwed into the tapped passage 4¹.

25 In the operation of the device compressed air passes through the passages 3^a, 4^a and 4^b to the annular passage 4^c; thence through the convergent air-passages to the tip of the nozzle. A portion of the air may enter the upper portion of the container C². When the device is operating, liquid rises through the tube 7 to the passage 4¹ and thence through 30 the central passages 5^a and 8^a to the tip of the nozzle. At the tip of the inner member 8, the liquid is atomized by the air and then is expelled through the passage 9^b.

35 In operating the device for applying varnish, for example, the large container C² may be used for most of the work. After finishing the painting operation, the container C² may be removed and the container C³, filled with a solvent, may be connected with the socket 14. The device may then be operated to force the solvent through the nozzle-tip, thus cleansing the parts of the tip portions of the nozzle. When necessary or desirable, the nozzle may be taken apart for 40 more thorough cleaning or for replacement of parts.

45 In many cases, it is desirable to use a number of containers carrying small quantities of varnishes of different colors. For this purpose, a plurality of small containers like the container C³ may be used to enable different colors to be applied, as desired.

50 At the end of the operation, air pressure within the container will be relieved by air passing to the annular passage 4^c and thence back to the compressor and out through the intake opening 2 to the atmosphere.

55 The foregoing detailed description has been given for clearness of understanding only, and no unnecessary limitations should be understood therefrom, but the appended claims should be construed as broadly as permissible, in view of the prior art.

60 What I regard as new, and desire to secure by Letters Patent, is:

1. In combination: a container cover equipped with a ring; and a nozzle comprising a pair of sections, one of said sections having a bearing extending through said ring, said sections having screw connections and having shoulders clamping the ring between them, said bearing having an annular air-passage communicating with the interior of said cap. 70

2. In a device of the character set forth, a ring having a depending stem and cap carried thereby, and a nozzle comprising a section having a central liquid-passage and equipped with a tube depending through a passage in said stem and said section having 80 an external bearing surface and an annular channel formed therein and forwardly convergent air-passages leading from said annular channel, said section having also at its rear end a central air-passage communicating with said annular passage, and a companion section having screw connection with said first-mentioned section, said ring being clamped between said sections and forming the outer wall of said annular passage. 85

3. In means of the character set forth, a container-cap equipped with a ring and having an air-passage leading from the interior of the cap to the interior of the ring and a liquid-tube extending freely through said passage, in combination with a nozzle comprising: a rear section having a central air-passage and provided at its front end with an interiorly threaded socket, an intermediate section having a bearing extending through said ring and an annular channel whose outer wall is formed by said ring, said intermediate section having at its rear end a threaded shank connected with said socket and a passage connecting said annular passage with the passage of said rear section, said intermediate section having forwardly convergent air-passages leading from said annular passage and having a central liquid-passage connected with said tube; a front section having convergent air-passages communicating with said first-mentioned convergent passages and having a central liquid-passage communicating with said first-mentioned liquid-passage; and a nozzle-tip 115 comprising an inner tip-member having a central liquid-passage and having convergent air-passages, and an outer cap-like tip-member, a nut clamping said inner tip-member to said front nozzle section, and a nut securing said cap-like tip-member to said first-mentioned nut. 100

4. In a device of the character set forth, a nozzle comprising a pair of sections provided with air-passages, one of said sections being provided with a liquid-passage, said sections having screw connections and one of said sections being provided with a bearing, and a container-cap having a ring 120

125

through which said bearing extends and which is clamped between said sections.

5. In a device of the character set forth, a nozzle comprising a pair of sections provided with air-passages, one of said sections being provided with a liquid-passage, said sections having screw connections and one of said sections being provided with a bearing, a container-cap having a plurality of sockets 10 of different diameters and equipped with a ring through which said bearing extends and which is clamped between said sections, said cap having an air-passage leading therethrough to the interior of said ring, and a 15 liquid-tube extending freely through the air-passage in said cap.

6. In a spraying device, a nozzle comprising three main sections consisting of a front section, a rear section, and an intermediate 20 section, said intermediate section having an annular air-passage and forwardly convergent air-passages leading therefrom and having a central rear air-passage communicating with said annular passage and said intermediate section having also a central liquid-passage, said rear section having a central air-passage communicating with the central air-passage of said intermediate section, and said front section having a central liquid- 25 passage communicating with the liquid-passage of said intermediate section and having forwardly convergent air-passages communicating with said first-mentioned convergent air-passages; a nozzle-tip comprising inner 30 and outer tip-members secured to said section; a container-cap having a ring clamped between said intermediate section and rear section; and a liquid-tube extending through 35 said container-cap and communicating with the liquid-passage of said intermediate section. 40
